CLAIM

The ornamental design for a vehicle interior as shown and described.

DESCRIPTION

FIG. 1 is a front right perspective view of a vehicle interior; FIG. 2 is a front left perspective view of the vehicle interior depicted in FIG. 1;

FIG. 3 is a rear right perspective view of the vehicle interior depicted in FIG. 1; and,

FIG. 4 is a rear left perspective view of the vehicle interior depicted in FIG. 1.

The short-dash-long-dash lines depict a boundary around the de-emphasized elements, which illustrate portions of the vehicle interior which form no part of the claimed design.
